Patented Mar. 19, 1968

210,526

FLUID HEAT EXCHANGER FOR AIR CONDITIONING AND REFRIGERATION SYSTEMS AND THE LIKE

Raymond A. Lo Turco, Wexford, Pa., assignor to Frick Company, Waynesboro, Pa., a corporation of Pennsylvania

Filed Sept. 1, 1967, Ser. No. 8,454

Term of patent 14 years

(Cl. D23—153)

FIG. 1

FIG. 2

FIG. 3

FIG. 1 is a view in perspective of the fluid heat exchanger for air conditioning and refrigeration systems and the like according to this invention.

FIG. 2 is a perspective view of the fluid heat exchanger shown in FIG. 1 from a different viewing point, and

FIG. 3 is a top plan view of the fluid heat exchanger illustrated in FIGS. 1 and 2 on a slightly smaller scale.

I claim:

The ornamental design for a fluid heat exchanger for air conditioning and refrigeration systems and the like, as shown.
